UNITED STATES PATENT OFFICE.

THORNTON F. SANBORN, OF NEW YORK, N. Y., ASSIGNOR TO SANBORN EVAPORATOR COMPANY, OF NEW YORK, N. Y., A CORPORATION OF DELAWARE.

TUBE COMBINED WITH HEATING, COOLING, AND EVAPORATING APPARATUS OR RECEPTACLES.

1,151,292.

Specification of Letters Patent. Patented Aug. 24, 1915.

Application filed July 25, 1912. Serial No. 711,599.

To all whom it may concern:

Be it known that I, THORNTON F. SANBORN, a citizen of the United States, residing at New York, county of New York, and 5 State of New York, have invented certain new and useful Improvements in Tubes Combined with Heating, Cooling, and Evaporating Apparatus or Receptacles, of which the following is a specification.

10 This invention relates to tubes, combined with heating, cooling, and evaporating apparatus or receptacles.

Heretofore tubes which have been combined with heating, cooling, evaporating 15 and other purposes requiring a tube with one end closed, have been provided with a plug or cap either welded, brazed, soldered, rolled or screwed thereto.

None of the foregoing methods of closing 20 the end of the tube have been satisfactory.

Where welding is resorted to, there is an uncertainty of the union of the plug or cap and tube, especially where a large number 25 of tubes are being produced, for while many would be substantially perfect, uniformity of the weld cannot be obtained and frequently imperfect welds occur which cannot be determined until the tube is actually put in use. Where brazing is resorted to, the

30 solder is subject to the action of any acids in contact with the tube, setting up a galvanic couple which by electrolytic action weakens the joint and causes leakage. If the tube is rolled to secure the plug, the 35 different coefficients of expansion of the plug and tube tend to cause opening of the joint and consequent leakage. Should the plug or cap be soldered, the joint is subject to galvanic action and cannot be reliably 40 formed. Should the plug or cap be screw-threaded, it is impossible to provide a steam and fluid tight joint.

My object is to provide a tube for receptacles or apparatus for heating, cooling, evaporating and other purposes which will be 45 provided with a closed end, constructed so that neither the tube nor the end have a joint, seam, weld or other connection of any kind whatsoever, whereby the defects here- 50 tofore set forth are entirely eliminated and leaks due to expansion, corrosive action of

acids or alkalies, or through galvanic or electrolytic action, wear, or other cause, are absolutely prevented.

In carrying out my invention, I provide 55 in combination with a wall of a heating, cooling, or evaporating receptacle or apparatus a seamlessly drawn and seamlessly closed metallic tube, one end of the tube being closed and the other end open, the 60 tube being without a seam, weld or joint from one end to the other.

The present invention has no reference to a stamped, pressed, brazed, welded or spun metallic article of any kind whatsoever and 65 consists of a seamlessly drawn and seamlessly closed tube combined with a heating, cooling, evaporating or other apparatus or receptacle as set forth.

Referring to the accompanying drawing, 70 1^a shows in section, more or less diagrammatically, a portion of the wall of any preferred or well-known heating, cooling, or evaporating apparatus or receptacle, and in longitudinal section, a tube 1 having closed 75 end 2 and open end 3, the tube being constructed and combined with the wall 1^a according to my present invention.

The tube is of a single homogeneous piece 80 of metal, seamless throughout its length and at its end, without a joint or connection of any kind whatsoever. The tube is produced by drawing as contradistinguished from welding, brazing, stamping, pressing or spinning. The tube may be provided with 85 any desired or preferred means for its attachment to the article, device or machine on which it is to be used or it may be secured to such article, device or machine in any desired manner, the present invention consisting in a seamlessly drawn and seamlessly closed tube combined with a heating, cooling, or evaporating apparatus or receptacle. 90

Having thus described my invention, what I claim as new and desire to secure by Letters Patent, is:—

1. The combination with a heating, cooling or evaporating receptacle or vessel, of a tube attached to a wall thereof and disposed internally of said receptacle or vessel, said tube having one end seamlessly drawn and completely closed and the other

end open, said tube being homogeneous throughout its length and closed end.

2. The combination with a heating, cooling or evaporating receptacle or vessel, of a 5 seamlessly drawn tube having one end open and its other end seamlessly drawn and completely closed, the open end of the tube being attached to a wall of said receptacle or ves-

sel and the tube being disposed internally of said receptacle.

In testimony whereof, I hereunto affix my signature in presence of two witnesses.

THORNTON F. SANBORN.
